UNITED STATES PATENT OFFICE

EUGENE AMBROZY, OF NEW YORK, N. Y.

CONSTRUCTION OF MARINE VESSELS.

1,193,965.

Specification of Letters Patent. Patented Aug. 8, 1916.

Application filed December 27, 1915. Serial No. 68,890.

To all whom it may concern:

Be it known that I, EUGENE AMBROZY, a citizen of the United States, and a resident of the city of New York, in the county of New York and State of New York, have invented certain new and useful Improvements in Construction of Marine Vessels, of which the following is a specification.

The present invention relates to marine vessels, or in other words to ships.

It pertains more particularly to marine vessels of the type described in application for U. S. Letters Patent, Ser. No. 27,355, filed by me on the 11th day of May, 1915.

In the said application, a vessel is described, comprising an outer hull and an inner hull, which hulls have a common keel, upon which rests a longitudinal bulk-head. To the said keel are fastened transverse plates having disposed along their outer edges channel-irons, which constitute the transverse frames of the said outer hull. A second set of channel-irons is secured to said plates and said bulk-head, forming the transverse frames of said inner hull. There are also means provided for connecting and bracing the two hulls. The outer hull has an impenetrable or puncture-proof skin or sides.

The main object of the present invention is to generally improve the construction of marine vessels of the class described in the above recited application by providing also the inner hull of the vessel with a puncture-proof skin or sides, and by dividing the space between the two hulls into transverse water-tight compartments.

With these and other objects in view, which will more fully appear as the nature of the invention is better understood, the same consists in the combination, arrangement and construction of parts hereinafter fully described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

Figure 1 is a transverse section midship of a vessel constructed in accordance with the present invention, the right-hand side of said section being shown incomplete in order to more clearly show the construction; Fig. 2 is a transverse section taken through a por-

tion of the vessel on an enlarged scale, showing the bracing means between the two hulls thereof; Fig. 3 is a section taken on line 3—3, of Fig. 2; Fig. 4 is a section taken on line 4—4 of Fig. 2; and Fig. 5 is a section taken on line 5—5 of Fig. 1.

In the drawings, the numeral 10 indicates the keel of the vessel, extending, as in all structures of this type, throughout the length of the vessel, and being made in the form of an I-beam, the lower flange 11 of which is wedge-shaped in cross section for the well known purpose. Above the keel is disposed a vertical bulk-head 12, extending from stem to stern and connected with the transverse frames of the vessel in a manner hereinafter to be described. This bulk-head divides, generally speaking, the hull into two longitudinal compartments, which communicate with each other through door-ways (not shown in the drawings).

The transverse frames of the vessel are each made of two substantially L-shaped plates 13, the outer contours of which correspond, of course, to the respective transverse cross sections of the vessel. These plates, which form the back-bones of the transverse frames, are disposed at suitable distances from each other and are united with auxiliary transverse frames, each comprising a pair of plates 14, the heights of which extend only one or two floors or decks above the bottoms, while the plates 13 extend to the uppermost deck of the vessel. The outer edges of the plates 13 and 14 are provided with substantially equi-distantly arranged parallel slots 16, the slots in the several plates being in alinement with each other for a purpose hereinafter to be described.

These slots run at right angles to the edge of a plate where said edge is straight, and in radial direction to the curve where said edge is curved, as for instance at the bilge. Parallel to the outer edge of each plate 13 and adjacent to the slotted portion thereof is riveted to each face of the same a channel-iron 17, for instance of U-shaped cross section, said channel-irons extending into the spaces formed between the flanges of the keel and forming together with the plates 13 the transverse frames of the outer hull of the vessel. In a similar manner are riveted to both faces of the plates 14 channel-irons 18, constituting with the plates 14 auxiliary transverse frames. The main and auxiliary transverse frames are spaced apart by chan-

nel-irons 19, which abut against the keel and are riveted to the latter, and also to the channel-irons 17 and 18.

A substantial distance above the channel-irons 17 and 18 there are riveted to both faces of each of the plates 13 and 14 channel-irons 20, said last named channel-irons resting upon the upper flange of the keel and extending toward the sides of the vessel 10 and thence upward, their outer ends being attached in any suitable manner to the channel-irons 17 and 18. The channel-irons 20 are spaced apart by longitudinal channel-irons 21, which abut against and are attached to the bulk-head 12 and to the said channel-irons 20. Inclined braces 22, in the form of channel-irons, are riveted to both faces of the plates 13 and 14, their lower ends being connected with the channel-irons 20 near to the inner ends of the latter, and the upper ends of said braces being suitably connected with the channel-irons 17 and 18, respectively.

In parallel relation to and flush with the inner edges of the plates 13 are riveted to both faces the latter channel-irons 23, resting upon and being attached to the braces 22, and forming with the latter the transverse frames of the inner hull of the vessel.

The plates 13 and 14 are provided with registering openings 24 for a purpose herein-after to be described. In rear of the channel-irons 23 and the braces 22 there are provided in the plates 13 and 14 substantially parallel slots 25 and 26, respectively, the slots 25 running from the openings 24 at right angles to the longitudinal axes of the channel-irons 23, and the slots 26 at right angles to the longitudinal axes of the braces 22. The channel-irons 20 are supported by stringers 27, made in the form of composite I-beams, which rest upon the transverse frames 17 and 18. Struts 28 connect the channel-irons 20 with the transverse frames 17 and 18 to further brace and strengthen the elements. The stringers 27 extend through the plates 13 and 14.

The transverse frames of the outer hull of the vessel are connected by longitudinal frames, which are constructed in the following manner: To both faces of each of the plates 13 and 14, and between the slots 16 therein, are attached angle-irons 29, which are bent into substantially O-shape, each of said angle-irons being disposed between two slots in the said plates and having a flange 30, that is disposed at right angles to the plane of the respective plate. The longitudinal frames, in the form of U-shaped stringers 31, have their flanges 32 disposed in the slot 16, to wit: In each slot there are disposed the flanges of two adjoining stringers, their bases 33 being riveted to the flanges 30 of the angle-irons 29. The outer faces of these stringers are

covered by a sheathing 34 of any suitable material. In parallel relation to the sheathing 34 there is provided a sheathing 35, inclosing together with the sheathing 34 the stringers or longitudinal frames 31. The sheathing 35 may be attached to the angle-irons 29 in any suitable manner, for instance by angle-iron pieces 35'. The sheathing 35 abuts against the outer flanges of the channel-irons 17 and 18. In order to have access to the interior of the stringers, as the riveting work is being done, there are provided in the sheathing 35 man-holes 35", which are closed by covers in the usual manner. The longitudinal frames run throughout the length of the vessel. To properly brace the longitudinal frames 31, there are provided brackets 36, having the same configuration as the angle-irons 29 above described. The brackets 36 run in parallel relation to the angle-irons 29, are disposed within the U-shaped stringers and attached to the latter and to the sheathing 35. In order to strengthen the sheathing 35, there are angle-irons 37 attached to the inner face of the said sheathing, said angle-irons running in parallel relation to the channel-irons 17 and 18.

The transverse frames of the inner hull are also connected by longitudinal frames. 95 These frames, denoted by the numeral 38, are, like the longitudinal frames of the outer hull, made in the form of U-shaped stringers, their flanges 38 being disposed in the slots 25 and 26 in the plates 13 and 14, 100 and fastened to the said plates by substantially O-shaped brackets 40, which are carried by the plates 13 and 14. To the inner faces of these longitudinal frames is fastened the sheathing 41 of the inner hull, 105 brackets 42 and angle-irons 43 serving to brace the same, the brackets 42 being disposed within the stringers 38, and the angle-irons 43 being attached to the inner face of the sheathing 41. In the sheathing 41 are 110 provided man-holes 44, covered in any suitable manner, to permit access into the stringers 38 when the riveting work is being performed. The sheathing 41 abuts against the outer flanges of the channel-irons 23 115 and braces 22.

The vessel may be provided with any suitable number of decks, each of which is formed by deck-beams 45, the inner ends of which are footed on stringers 46, which are 120 attached to the bulk-head 12, while their outer ends are connected by angle-irons 47, or similar means, with the channel-irons 23. The deck-beams 45 are connected by longitudinal stringers 53. Immediately below 125 each deck-beam is located between the inner and outer hulls a bracing girder 54, comprising in the case illustrated in the drawings a plurality of horizontal plates 55, which are united, for instance by transverse 130

I-beams 56. Each girder extends from plate 13 to plate 13 and is supported by keelsons 57, for instance in the form of U-shaped beams, which are suitably attached to the sheathing 35. The inner ends of these 5 girders are secured, for instance by angle-irons 58 to the stringers 38. Flush with the deck-beams 45 are attached to the channel-irons 23 beams 59, resting upon the upper 10 most plates of the girders 54, and being connected with transverse beams 60, that are attached to the stringers 38 and form continuations of the deck-beams 45. The deck-beams 45 and 60 are covered by a suitable 15 deck plating 61, in which may be provided the necessary hatches, as usual.

Struts 62 connect the channel-irons 20 with one set of stringers 46, and struts 63 20 with the braces 22 with another set of stringers 46, said struts serving to keep, in addition to the elements above mentioned, the said channel-irons and braces in proper relation to the longitudinal bulk-head 12 both against inner and outer pressure. Inasmuch 25 as the sides of the outer hull and the channel-irons 20, which form, as will herein-after appear, one of the bottoms of the vessel, are connected with the bulk-head, the pressure, to which they are subjected, is 30 transferred to and taken up by the bulk-head. To the underfaces of the upper flanges of the channel-irons 20 is riveted a 35 sheathing 64, thereby forming an intermediate bottom of the vessel between the bottom of the outer and inner hulls thereof.

From the foregoing it appears that the vessel comprises an inner hull and an outer hull, each of which has transverse frames and longitudinal frames. The longitudinal 40 frames form for each hull an impenetrable wall, the sheathing 35, covering the inner face of the wall of the outer hull, dividing the said wall into a plurality of longitudinal water-tight compartments, and the skin 41 45 upon the inner stringers, dividing likewise the wall of the inner hull into longitudinal water-tight compartments. The bracing girders 54 form longitudinal water-tight compartments between the inner and outer 50 hulls, and, inasmuch as the openings 24 above described are normally closed by doors 65, these compartments are subdivided into transverse compartments. Should, therefore, the outer hull be penetrated, 55 water will rush only into those compartments between the two hulls which are adjacent to the injured portion of the outer hull. Should the outer bottom be injured, water will not reach the lowermost deck 60 inasmuch as the sheathing 64 forms, as above described, a false bottom between the two hulls. Inasmuch as this last named bottom and the bottom of the outer hull are properly braced and armored, as it were, 65 by the stringers 27 and struts 28, it is almost

impossible to stave in the same. The two hulls being braced by the girders 54 and connected by the transverse plates 13 and 14, cannot separate.

What I claim is:—

1. An iron vessel comprising an outer and an inner hull having a common keel, transverse plates fastened to said keel, channel-irons disposed along the outer edges of said plates and attached to the latter and to said keel, thereby constituting the transverse frames of said outer hull, a second set of channel-irons secured to said plates, forming the transverse frames of said inner hull, longitudinal frames connecting the transverse frames of said outer hull, and longitudinal frames connecting the transverse frames of said inner hull, both sets of longitudinal frames being disposed exterior of their respective transverse frames. 70 75 80 85

2. An iron vessel comprising an outer and an inner hull having a common keel, transverse plates fastened to said keel, channel-irons disposed along the outer edges of said plates and attached to the latter and to said keel, thereby constituting the transverse frames of said outer hull, a second set of channel-irons secured to said plates, forming the transverse frames of said inner hull, longitudinal frames connecting the transverse frames of said outer hull, longitudinal frames connecting the transverse frames of said inner hull, both sets of longitudinal frames being disposed exterior of their respective transverse frames, and a sheathing 90 95 100 applied to the inner faces of both sets of longitudinal frames. 100

3. An iron vessel comprising an outer and an inner hull having a common keel, transverse plates fastened to said keel, channel-irons disposed along the outer edges of said plates and attached to the latter and to said keel, thereby constituting the transverse frames of said outer hull, a second set of channel-irons secured to said plates, forming the transverse frames of said inner hull, longitudinal frames connecting the transverse frames of said outer hull, longitudinal frames connecting the transverse frames of said inner hull, both sets of longitudinal frames being disposed exterior of their respective transverse frames, a sheathing applied to the inner faces of both sets of longitudinal frames, and a sheathing applied to the outer face of the longitudinal 110 115 120 frame of said outer hull. 120

4. An iron vessel comprising a keel, transverse plates attached to said keel having slots in their outer edge portions, channel-irons disposed in parallel relation to the outer edges of said plates and attached to said keel, thereby constituting the transverse frames of the hull, U-shaped stringers having their flanges disposed in the slots of said plates, thus forming the longitudinal 125 130

- frames of said hull, the abutting flanges of each adjacent pair of stringers being disposed in a common slot, means for fastening said stringers to said plates, a sheathing secured to the outer faces of said stringers, and a sheathing applied to the inner faces of said stringers.
5. An iron vessel comprising a keel, transverse plates attached to said keel having 10 slots in their outer edge portions, channel-irons disposed in parallel relation to the outer edges of said plates and attached to said keel, thereby constituting the transverse frames of the hull, U-shaped stringers 15 having their flanges disposed in the slots of said plates, thus forming the longitudinal frames of said hull, the abutting flanges of each adjacent pair of stringers being disposed in a common slot, means for fastening 20 said stringers to said plates, and a sheathing applied to the inner faces of said stringers.
6. An iron vessel comprising a keel, transverse plates attached to said keel having 25 slots in their outer edge portions, channel-irons disposed in parallel relation to the outer edges of said plates and attached to said keel, thereby constituting the transverse frames of the hull, said slots running from 30 the outer edges of said plates to the channel-irons thereon, U-shaped stringers having their flanges disposed in the slots of said plates, thus forming longitudinal frames of the hull, the abutting flanges of each adjacent 35 pair of stringers being disposed in a common slot, means for fastening said stringers to said plates, and a sheathing secured to the inner faces of said stringers and abutting against said channel-irons.
- 40 7. An iron vessel comprising a keel, transverse plates attached to said keel having slots in their outer edge portions, channel-irons disposed in parallel relation to the outer edges of said plates and attached to 45 said keel, thereby constituting the transverse frames of the hull, said slots running from the outer edges of said plates to the channel-irons thereon, U-shaped stringers having 50 their flanges disposed in the slots of said plates, thus forming longitudinal frames of the hull, the abutting flanges of each adjacent pair of stringers being disposed in a common slot, means for fastening said stringers to said plates, a sheathing secured to the inner faces of said stringers and abutting against said channel-irons, and a sheathing applied to the outer faces of said stringers.
- 55 8. An iron vessel comprising a keel, transverse plates attached to said keel having 60 slots in their outer edge portions, said slots running at right angles to the edge where said edge is straight and radially where said edge is curved, U-shaped stringers having 65 their flanges disposed in the slots of said plates, thus forming the longitudinal frames of the hull, the abutting flanges of each adjacent pair of stringers being disposed in a common slot, means for fastening said stringers to said plates, and a sheathing secured to the inner faces of said stringers.
9. An iron vessel comprising a keel, transverse plates attached to said keel having 70 slots in their outer edge portions, said slots running at right angles to the edge where said edge is straight and radially where said edge is curved, U-shaped stringers having 75 their flanges disposed in the slots of said plates, thus forming the longitudinal frames of the hull, the abutting flanges of each adjacent pair of stringers being disposed in a common slot, means for fastening said stringers to said plates, a sheathing secured to the inner faces of said stringers, and a sheathing applied to the outer faces of said 80 stringers.
10. An iron vessel comprising an outer and an inner hull having a common keel, transverse plates fastened to said keel, channel-irons disposed in parallel relation to the 90 outer edge of said plates and attached to the latter and to said keel, thereby constituting the transverse frames of said outer hull, a second set of channel-irons secured to said plates forming the transverse frames of said 95 inner hull, said plates being provided with a set of slots running from the outer edges thereof to the transverse frames of said outer hull and with a set of slots running 100 from the transverse frames of said inner hull toward the frames of said outer hull, U-shaped stringers having their flanges disposed in the slots of said plates, one set of 105 said stringers forming the longitudinal frames of the outer hull and the other set the longitudinal frames of said inner hull, the abutting flanges of each adjacent pair of stringers being disposed in a common slot, means for fastening said stringers to 110 said plates, and a separate sheathing secured to the inner face of each set of stringers.

Signed at New York, in the county of New York, and State of New York, this 21st day of Dec., A. D. 1915.

EUGENE AMBROZY.
